UNITED STATES PATENT OFFICE.

GUSTAVE NARCISSE MICHAUD, OF ST. PAUL, MINNESOTA.

STAMP AND INKING-PAD HOLDER.

1,237,538.

Specification of Letters Patent. Patented Aug. 21, 1917.

Application filed February 8, 1917. Serial No. 147,512.

To all whom it may concern:

Be it known that I, GUSTAVE NARCISSE MICHAUD, a citizen of the United States, residing at St. Paul, in the county of Ramsey and State of Minnesota, have invented new and useful Improvements in Stamp and Inking-Pad Holders, of which the following is a specification.

Unnecessary labor is required in the use 10 of rubber stamps as they are ordinarily un-sistematically arranged in more or less in-convenient receptacles, apart from the ink pads.

It is the object of my present invention to 15 provide an improved holder adapted to receive and conveniently correlate an inking pad with a plurality of stamps.

A further object is to provide a device 20 of this kind having movable partitions, adjustable to conform to stamps of various sizes and adapted to receive an inking pad, which forms a common bottom for said compartments.

A further object is to provide a device of 25 this character designed so that the stamps when in place substantially seal the pad and minimize evaporation of the ink.

In the drawings, Figure 1 is a perspective view of a holder embodying my invention, 30 the cover on said holder being illustrated in open position and one of the partitions in the tray being broken away to more clearly show the construction thereof; Fig. 2 is a central transverse sectional view; Fig. 3 is a central longitudinal sectional view; and Fig. 4 is a detail plan view of the tray, certain portions thereof being broken away to illustrate otherwise concealed parts.

Referring to the drawings, I have used 40 the reference letter A to indicate the tray. Partitions B are arranged within the tray and form compartments for stamps which rest upon an inking pad 10 in said tray. A cover 11 is hinged on one side of the tray, 45 or otherwise suitably applied thereto.

The tray A is a shallow rectangular receptacle, preferably constructed from a blank of light sheet metal. One wall of the tray is formed with an opening 12 to receive 50 the inking pad 10, which rests in the bottom of the tray and closes said opening 12, as illustrated in Fig. 1. The upper edges of the walls of said tray are turned inward to form flanges 14 whose lower edges rest closely 55 adjacent to the inking surface of the pad 10.

Upon each ledge 13, I secure a strip of metal *a* which is folded upon a longitudinal line; the upper fold 15 is substantially equal in width to the width of the ledge and the 60 lower fold 16 is somewhat narrower, as shown in the drawings. The lower folds 16 of said strips *a* are soldered, or otherwise suitably secured upon the ledges 13, so that a continuous inner marginal groove 17 is 65 formed in the walls of the tray. The partitions B are formed with downwardly extending flanges 18 of equal breadth, the lower edges of which rest closely adjacent to the upper surface of the pad 10. The 70 horizontal webs 19 at the ends of said partitions B project a slight distance beyond the flanges 18 forming extensions 20, which are serrated at their extremities and inserted in the grooves 17 at opposite sides of the tray. 75 The edge of the lower fold 16 in one groove 17 is serrated to engage and secure the adjacent serrated extensions 20 of said partitions, and a serrated keeper bar 21, is placed in the opposite groove 17. This bar 21 is 80 hinged at one end on a pin 22 in the strip *a* and is supplied with a lug 23 and handle 24 at its other end. A slot 25 in said strip *a* permits said bar to swing outward (Fig. 85 4) and a spring catch 26, formed with a releasing arm 27, extends through said slot 25 and engages the lug 23 on the bar to secure the same in normal position, wherein the teeth on said bar intermesh with the teeth on the adjacent serrated extensions 20 90 of the partitions and hold said partitions in place. The cover 10 is secured by means of suitable hinges 28 upon the tray and when closed rests snugly against a sealing strip 29 95 on the upper edge of the tray.

In use, an inking pad 10 is inserted through the opening 12 in the bottom of the tray. The keeper bar 21 is swung outward and the partitions B adjusted to fit rows of stamps between them, whereupon the keeper 100 bar is swung inward and latched to secure said partitions. When the cover is open, the stamps are readily accessible and close the compartments occupied thereby, thus preventing evaporation of the inking material 105 from the pad. When the device is not in use, the cover 11 is closed to further protect the contents of the tray.

It will be seen that my improved stamp holder possesses at least three substantial advantages: (1) the compartments may be easily adjusted to fit the particular stamps 110

required, (2) the stamps are housed in an orderly manner and in a position for immediate inking and use, and (3) the placing of the stamps upon the pad protects both against deterioration caused by evaporation and dust.

Having described my invention, what I claim as new and desire to protect by Letters Patent, is:

- 10 1. In a device of the class described, a tray having inner marginal grooves in opposite walls thereof, an inking pad in the bottom of the tray, partitions in said tray forming compartments with the pad as a base, the ends of said partitions being serrated and inserted in said grooves, a fixed serrated keeper in one of the grooves and a hinged serrated keeper in the opposite groove, a latch for said keeper, both of said keepers being adapted to co-act with the ends of the partitions and secure the same in predetermined positions.
- 15 2. In a device of the class described, a tray having inner marginal grooves in opposite walls thereof, an inking pad in the bottom of the tray, partitions in said tray forming compartments with the pad as a base, the ends of said partitions being serrated and inserted in said grooves, a fixed serrated keeper in one of the grooves and a hinged serrated keeper in the opposite groove, a latch for said keeper, both of said keepers being adapted to co-act with the
- 20
- 25
- 30

ends of the partitions and secure the same in predetermined positions, and a cover for the tray.

3. In a device of the class described, a tray having an opening at one side thereof and a serrated inner side, a hinged serrated keeper parallel with said side, an inking pad adapted to be removably inserted in said opening, partitions in said tray above said pad forming compartments in which the stamps rest upon the pad, said partitions being serrated at their ends and having one end engaging the serrations of the side, and the other engaging the keeper, whereby said partition may be adjusted to form compartments of various sizes.

4. In a device of the class described, a tray having the upper edges of its walls turned inward then downward to form depending flanges, one of said flanges being serrated, an inking pad resting in the bottom of said tray beneath said flanges, partitions having serrated ends in the tray above said pad, and a hinged serrated keeper in the side opposite said serrated flange co-acting with the ends of said partitions to secure the same in predetermined positions, said flanges and partitions forming compartments adapted to receive and be closed by stamps which rest upon said pad.

Whereof, I have hereunto subscribed my name to this specification.

GUSTAVE NARCISSE MICHAUD.
